United States Patent Office.

MARTIN A. ROWE, OF MARTINSVILLE, ILLINOIS.

Letters Patent No. 102,323, dated April 26, 1870.

IMPROVEMENT IN CRANK-MOTION.

The Schedule referred to in these Letters Patent and making part of the same.

To all whom it may concern:

Be it known that I, MARTIN A. ROWE, of Martinsville, in the county of Clark and State of Illinois, have invented a new and Improved Crank-Motion; and I do hereby declare that the following is a full, clear, and exact description thereof, reference being had to the accompanying drawings making part of this specification, in which—

Figure 1 is a view of one side of the device.

Figure 2 is a diametrical section through the line *m n*.

Figure 3 is a diagram showing the different positions of the wrist-pin relatively to the axis about which it revolves, while revolving.

Similar letters of reference indicate corresponding parts in the several figures.

The nature of my invention and improvement in cranks for driving various kinds of machinery consists in applying a wrist-pin to a reciprocating arm or slide which is actuated by means of a stationary elliptical guide and swivel-dogs, in such manner that the wrist-pin will travel in an elliptical path in its revolution about an axis, as will be hereinafter described.

To enable others skilled in the art to understand my invention I will describe its construction and operation.

In the accompanying drawings—

A represents a crank-wheel which serves as a balance-wheel, and also as a support for a slide, *B*.

This slide *B* is arranged diametrically across one side of wheel *A*, and kept in place by the blocks *a a a a*, which latter will allow the slide free endwise motion.

D is the shaft of wheel *A*, to which this wheel is keyed; and

S is an oblong slot which is made through slide *B* for receiving through it shaft *D*.

The wrist-pin, to which a pitman is applied, is secured to the slide *B* near one end, and extended through an oblong slot, *p*, so as to project from the surface of wheel *A*, opposite the side on which the slide is applied, as shown in figs. 2 and 3.

C is an elliptical guide, which is secured rigidly to the frame which supports the shaft *D*, and which is designed for moving slide *B*, and causing its wrist-pin to describe an ellipse in its revolution about the axis of shaft *D*.

To effect this movement of the wrist-pin *W*, I connect the slide *B* to the elliptical guide *C* by means of two swivel-jaws which are respectively pivoted to a swivel-plate, *E*.

The plate *E* is connected to slide *B* by means of a pivot, *r*, shown in fig. 2; and the jaw *g* is connected to plate *E* by means of pivot *i*.

This jaw *g* is applied so as to slide against the inner side of the elliptical guide *C*, and the impinging-surface of this jaw is slightly rounded, so as to accommodate itself to the shape of said guide.

The jaw which slides on the outer side of the elliptical guide *C* consists of a central portion, *e*, and two curved spring arms, *e' e'*, which parts will accommodate themselves to the shape of the guide *C* in their revolution around it.

The jaw *e' e'* is pivoted at *j* to the swivel-plate *E*.

It will be seen from the above description that as the wrist-pin is revolved about the axis of shaft *D* it will describe the ellipse indicated by dotted line *y*, in fig. 3, thereby practically increasing the length of crank in its passage through every alternate quarter of its revolution.

Having described my invention,

What I claim as new, and desire to secure by Letters Patent, is—

1. The combination of the crank-arm or slide *B*, wrist-pin wheel or crank *A*, elliptical guide *C*, and connecting devices between the said slide and the guide *C*, substantially as and for the purpose described.

2. The swivel-jaws *g e e' e'*, applied to a swivel-plate *E* on the wrist-pin slide *B*, in combination with the elliptical guide *C*, substantially as described.

MARTIN A. ROWE.
